9 Claims. (Cl. 71—2.6)

This application is a continuation-in-part of our application Serial No. 753,891, filed August 8, 1958, now abandoned.

This invention relates to certain chloroalkyl and bromoalkyl esters of disubstituted thiocarbamic acids as herbicides, and as new compounds. More specifically, the invention relates to compounds of the general formula

wherein R_1 is a lower chloroalkyl or bromoalkyl radical, R_2 is a lower alkyl radical, a lower chloroalkyl radical, a lower alkenyl radical, a lower chloroalkenyl radical or an alkynyl radical, and R_3 is a lower alkyl radical, a lower cycloalkyl radical, a lower chloroalkyl radical or a lower alkenyl radical. Typical non-limiting examples of the various substituents are as follows:

R_1	R_2	R_3	
ClCH_2CH_2	C_2H_5	C_2H_5	(R-2217)
ClCH_2CH_2	$\text{n-C}_3\text{H}_7$	$\text{n-C}_3\text{H}_7$	(R-2218)
ClCH_2CH_2	CH_3	$\text{n-C}_3\text{H}_6$	(R-2513)
ClCH_2CH_2	C_2H_5	$\text{n-C}_3\text{H}_6$	(R-2514)
ClCH_2CH_2	C_2H_5	cyclohexyl	(R-2515)
ClCH_2CH_2	$\text{CH}_2=\text{CHCH}_2$	$\text{CH}_2=\text{CHCH}_2$	(R-2516)
ClCH_2CH_2	$\text{CH}_2=\text{CHCH}_2$	$\text{n-C}_3\text{H}_7$	(R-2503)
ClCH_2CH_2	$\text{CH}_2=\text{CHCH}_2$	$\text{i-C}_3\text{H}_7$	(R-2517)
ClCH_2CH_2	$\text{CH}_2=\text{CHCH}_2$	$\text{i-C}_4\text{H}_9$	(R-2505)
ClCH_2CH_2	$\text{CH}_2=\text{C}(\text{Cl})\text{CH}_2$	$\text{n-C}_3\text{H}_7$	(R-2507)
ClCH_2CH_2	$\text{CH}_2=\text{C}(\text{Cl})\text{CH}_2$	$\text{CH}_2=\text{CHCH}_2$	(R-2508)
ClCH_2CH_2	$\text{CICH}=\text{CHCH}_2$	C_2H_5	(R-2509)
ClCH_2CH_2	$\text{CICH}=\text{CHCH}_2$	$\text{n-C}_3\text{H}_7$	(R-2525)
ClCH_2CH_2	$\text{CH}_2=\text{C}(\text{CH}_3)\text{CH}_2$	C_2H_5	(R-2518)
ClCH_2CH_2	$\text{CH}_2=\text{C}(\text{CH}_3)\text{CH}_2$	$\text{n-C}_3\text{H}_7$	(R-2519)
ClCH_2CH_2	$\text{CH}_2=\text{C}(\text{CH}_3)\text{CH}_2$	$\text{CH}_2=\text{CHCH}_2$	(R-2520)
ClCH_2CH_2	$\text{CH}_2=\text{C}(\text{CH}_3)\text{CH}_2$	$\text{n-C}_3\text{H}_7$	(R-2523)
ClCH_2CH_2	$\text{HC}=\text{CCH}_2$	CICH_2CH_2	(R-2526)
ClCH_2CH_2	CICH_2CH_2	$\text{CH}_3\text{CH}_2\text{CICH}_2$	(R-2527)
ClCH_2CH_2	$\text{CH}_3\text{CH}_2\text{CICH}_2$	C_2H_5	(R-2626)
$\text{ClCH}_2\text{CH}_2\text{CH}_2$	C_2H_5	$\text{n-C}_3\text{H}_7$	(R-2629)
$\text{ClCH}_2\text{CH}_2\text{CH}_2$	$\text{n-C}_3\text{H}_7$	$\text{n-C}_4\text{H}_9$	(R-2632)
$\text{ClCH}_2\text{CH}_2\text{CH}_2$	C_2H_5	$\text{CH}_2=\text{CHCH}_2$	(R-2630)
$\text{ClCH}_2\text{CH}_2\text{CH}_2$	$\text{CH}_2=\text{CHCH}_2$	$\text{n-C}_3\text{H}_7$	(R-2633)
$\text{ClCH}_2\text{CH}_2\text{CH}_2$	$\text{CH}_2=\text{C}(\text{CH}_3)\text{CH}_2$	$\text{n-C}_3\text{H}_7$	(R-2634)
$\text{ClCH}_2\text{CH}_2\text{CH}_2$	$\text{CH}_2=\text{C}(\text{CH}_3)\text{CH}_2$	$\text{CH}_2=\text{CHCH}_2$	(R-2636)
$\text{ClCH}_2\text{CH}_2\text{CH}_2$	$\text{CH}_2=\text{C}(\text{Cl})\text{CH}_2$	$\text{n-C}_3\text{H}_7$	(R-2640)
$\text{ClCH}_2\text{CH}_2\text{CH}_2$	$\text{CICH}=\text{CHCH}_2$	$\text{CH}_2=\text{CHCH}_2$	(R-2641)
$\text{ClCH}_2\text{CH}_2\text{CH}_2$	$\text{HC}=\text{CCH}_2$	$\text{n-C}_3\text{H}_7$	(R-2643)
$\text{ClCH}_2\text{CH}_2\text{CH}_2$	CICH_2CH_2	CICH_2CH_2	(R-2644)
BrCH_2CH_2	C_2H_5	C_2H_5	(R-2939)
BrCH_2CH_2	$\text{n-C}_3\text{H}_7$	$\text{n-C}_3\text{H}_7$	(R-2941)
BrCH_2CH_2	$\text{n-C}_4\text{H}_9$	C_2H_5	(R-2946)
BrCH_2CH_2	$\text{CH}_2=\text{CHCH}_2$	$\text{CH}_2=\text{CHCH}_2$	(R-2948)
BrCH_2CH_2	$\text{CH}_2=\text{CHCH}_2$	$\text{n-C}_3\text{H}_7$	(R-2949)
BrCH_2CH_2	$\text{CH}_2=\text{C}(\text{CH}_3)\text{CH}_2$	C_2H_5	(R-2952)
BrCH_2CH_2	$\text{CH}_2=\text{C}(\text{CH}_3)\text{CH}_2$	$\text{CH}_2=\text{CHCH}_2$	(R-2958)
$\text{BrCH}_2\text{CH}_2\text{CH}_2$	C_2H_5	C_2H_5	(R-2962)
$\text{BrCH}_2\text{CH}_2\text{CH}_2$	$\text{n-C}_3\text{H}_7$	$\text{n-C}_3\text{H}_7$	(R-2969)
$\text{BrCH}_2\text{CH}_2\text{CH}_2$	$\text{n-C}_4\text{H}_9$	CH_3	(R-2978)
$\text{BrCH}_2\text{CH}_2\text{CH}_2$	$\text{CH}_2=\text{CHCH}_2$	$\text{CH}_2=\text{CHCH}_2$	(R-2984)
$\text{BrCH}_2\text{CH}_2\text{CH}_2$	$\text{CH}_2=\text{CHCH}_2$	$\text{n-C}_3\text{H}_7$	(R-2987)
$\text{BrCH}_2\text{CH}_2\text{CH}_2$	$\text{CH}_2=\text{C}(\text{CH}_3)\text{CH}_2$	C_2H_5	(R-2990)

The novel compounds of the present invention may be made in accordance with the following non-limiting examples. Code numbers have been assigned to each compound and are used throughout the balance of the application.

Example I (R-2217).—8.5 g. (0.048 mole) of 2-hydroxyethyl *N,N*-diethylthiocarbamate was dissolved in 25 cc. of benzene and 1 drop of pyridine was added. The solution was cooled to 2½° C. and 7.2 g. (0.060 mole) of thionyl chloride was rapidly added. The temperature of the mixture rose rapidly to 24° C. while still in the ice

bath and slowly to 35° C. after removal from the ice bath. The mixture was then brought to reflux, held at reflux for ½ hour, cooled to room temperature, diluted with 100 cc. of ethyl ether and washed with three—25 cc. portions of water. The ether solution was dried over anhydrous magnesium sulfate, filtered and the filtrate was concentrated on the steam bath. The residual liquid was fractionally distilled. There was obtained 6.8 g. (72.2% yield) of 2-chloroethyl *N,N*-diethylthiocarbamate, B.P. (20 mm.) 144–145° C., n_D^{20} 1.5011.

Analysis.—Calculated for $\text{C}_7\text{H}_{14}\text{ClNOS}$: N=7.16%; Cl=18.1%. Found: N=7.05%; Cl=18.06%.

Example II (R-2503).—1.00 g. (6.29×10^{-3} moles) of 2-chloroethyl chlorothiolicformate was dissolved in 10 cc. of ethyl ether and a solution of 1.40 g. (13.8×10^{-3} moles) of *N*-allyl-*n*-propylamine in 15 cc. of ethyl ether was added rapidly. An exothermic reaction ensued and *N*-allyl-*n*-propylamine hydrochloride precipitated. 10 cc. of water was added, the mixture was transferred to a separatory funnel, 25 cc. more ethyl ether was added and the aqueous layer was separated. The ether layer was then washed with two—10 cc. portions of dilute hydrochloric acid (1 cc. of concentrate hydrochloric acid made up to a volume of 10 cc. with water) and one—10 cc. portion of water. The ether solution was then dried over anhydrous magnesium sulfate, filtered and evaporated on a warm hot plate under a stream of argon. There was obtained as a residual liquid 1.24 g. (89% yield) of 2-chloroethyl *N*-allyl-*N*-*n*-propylthiocarbamate, n_D^{20} 1.5068.

Analysis.—Calculated for $\text{C}_9\text{H}_{16}\text{ClNOS}$: N=6.32%. Found: N=6.30%.

Example III (R-2505).—When the general procedure of Example II was repeated except that 1.00 g. (6.29×10^{-3} moles) of 2-chloroethyl chlorothiolicformate and 1.56 g. (13.8×10^{-3} moles) of *N*-allyl-*i*-butyl amine were employed, there was obtained 1.48 g. (63.5% yield) of 2-chloroethyl *N*-allyl-*N*-*i*-butylthiocarbamate, n_D^{20} 1.5018.

Analysis.—Calculated for $\text{C}_{10}\text{H}_{18}\text{ClNOS}$: N=5.94%. Found: N=6.04%.

Example IV (R-2507).—When the general procedure of Example II was repeated except that 1.00 g. (6.29×10^{-3} moles) of 2-chloroethyl chlorothiolicformate and 1.84 g. (13.8×10^{-3} moles) of *N*-2-chloroallyl-*n*-propylamine were employed, there was obtained 1.40 g. (87% yield) of 2-chloroethyl *N*-2-chloroallyl-*N*-*n*-propylthiocarbamate, n_D^{20} 1.5181.

Analysis.—Calculated for $\text{C}_9\text{H}_{15}\text{Cl}_2\text{NOS}$: N=5.47%. Found: N=5.71%.

Example V (R-2508).—When the general procedure of Example II was repeated except that 1.00 g. (6.29×10^{-3} moles) of 2-chloroethyl chlorothiolicformate and 1.82 g. (13.8×10^{-3} moles) of *N*-2-chloroallyl-allylamine were employed, there was obtained 1.46 g. (91.3% yield) of 2-chloroethyl *N*-2-chloroallyl-*N*-allylthiocarbamate, n_D^{20} 1.5291.

Analysis.—Calculated for $\text{C}_8\text{H}_{13}\text{Cl}_2\text{NOS}$: N=5.51%. Found: N=5.51%.

Example VI (R-2509).—When the general procedure of Example II was repeated except that 1.00 g. (6.29×10^{-3} moles) of 2-chloroethyl chlorothiolicformate and 1.65 g. (13.8×10^{-3} moles) of *N*-3-chloroallyl-ethylamine were employed, there was obtained 1.39 g. (91.5% yield) of 2-chloroethyl *N*-3-chloroallyl-*N*-ethylthiocarbamate, n_D^{20} 1.5283.

Analysis.—Calculated for $\text{C}_8\text{H}_{13}\text{Cl}_2\text{NOS}$: N=5.78%. Found: N=5.93%.

Example VII (R-2215).—When the general procedure of Example II was repeated except that 1.30 g. (8.18×10^{-3} moles) of 2-chloroethyl chlorothiolicformate and 1.82 g. (18.0×10^{-3} moles) of di-*n*-propylamine were

employed, there was obtained 1.78 g. (97.3% yield) of 2-chloroethyl N,N-di-n-propylthiolcarbamate, n_D^{30} 1.4944.

Analysis.—Calculated for $C_9H_{18}ClNO$: N=6.27%. Found: N=6.02%.

Example VIII (R-2513).—When the general procedure of Example II was repeated except that 1.30 g. (8.18×10^{-3} moles) of 2-chloroethyl chlorothiolformate and 1.57 g. (18.0×10^{-3} moles) of N-methyl-n-butylamine were employed, there was obtained 1.71 g. (100% yield) of 2-chloroethyl N-methyl-N-n-butylthiolcarbamate, n_D^{30} 1.4988.

Analysis.—Calculated for $C_8H_{16}ClNO$: N=6.69%. Found: N=6.50%.

Example IX (R-2514).—When the general procedure of Example II was repeated except that 1.30 g. (8.18×10^{-3} moles) of 2-chloroethyl chlorothiolformate and 1.82 g. (18.0×10^{-3} moles) of N-ethyl-n-butylamine were employed, there was obtained 1.77 g. (96.8% yield) of 2-chloroethyl N-ethyl-N-n-butylthiolcarbamate, n_D^{30} 1.4940.

Analysis.—Calculated for $C_9H_{18}ClNO$: N=6.27%. Found: N=6.55%.

Example X (R-2515).—When the general procedure of Example II was repeated except that 1.30 g. (8.18×10^{-3} moles) of 2-chloroethyl chlorothiolformate and 2.28 g. (18.0×10^{-3} moles) of N-ethylcyclohexylamine were employed, there was obtained 2.02 g. (99.0% yield) of 2-chloroethyl N-ethyl-N-cyclohexylthiolcarbamate, n_D^{30} 1.5143.

Analysis.—Calculated for $C_{11}H_{20}ClNO$: N=5.61%. Found: N=5.50%.

Example XI (R-2516).—When the general procedure of Example II was repeated except that 1.30 g. (8.18×10^{-3} moles) of 2-chloroethyl chlorothiolformate and 1.75 g. (18.0×10^{-3} moles) of diallylamine were employed, there was obtained 1.65 g. (91.6% yield) of 2-chloroethyl N,N-diallylthiolcarbamate, n_D^{30} 1.5180.

Analysis.—Calculated for $C_9H_{14}ClNO$: N=6.38%. Found: N=6.23%.

Example XII (R-2517).—When the general procedure of Example II was repeated except that 1.30 g. (8.18×10^{-3} moles) of 2-chloroethyl chlorothiolformate and 1.78 g. (18×10^{-3} moles) of N-allyl-i-propylamine were employed, there was obtained 1.73 g. (95.5% yield) of 2-chloroethyl N-allyl-N-i-propylthiolcarbamate, n_D^{30} 1.5090.

Analysis.—Calculated for $C_9H_{16}ClNO$: N=6.32%. Found: N=6.36%.

Example XIII (R-2518).—When the general procedure of Example II was repeated except that 1.30 g. (8.18×10^{-3} moles) of 2-chloroethyl chlorothiolformate and 1.78 g. (18×10^{-3} moles) of N-methallylethylamine were employed, there was obtained 1.28 g. (70.6% yield) of 2-chloroethyl N-methallyl-N-ethylthiolcarbamate, n_D^{30} 1.5080.

Analysis.—Calculated for $C_9H_{16}ClNO$: N=6.32%. Found: N=6.48%.

Example XIV (R-2519).—When the general procedure of Example II was repeated except that 1.30 g. (8.18×10^{-3} moles) of 2-chloroethyl chlorothiolformate and 2.04 g. (18.0×10^{-3} moles) of N-methallyl-n-propylamine were employed, there was obtained 1.77 g. (91.7% yield) of 2-chloroethyl N-methallyl-N-n-propylthiolcarbamate, n_D^{30} 1.5029.

Analysis.—Calculated for $C_{10}H_{18}ClNO$: N=5.94%. Found: N=5.82%.

Example XV (R-2520).—When the general procedure of Example II was repeated except that 1.30 g. (8.18×10^{-3} moles) of 2-chloroethyl chlorothiolformate and 2.00 g. (18×10^{-3} moles) of N-methallylallylamine were employed, there was obtained 1.75 g. (91.6% yield) of 2-chloroethyl N-methallyl-N-allylthiolcarbamate, n_D^{30} 1.5149.

Analysis.—Calculated for $C_{10}H_{16}ClNO$: N=5.94%. Found: N=5.80%.

Example XVI (R-2523).—When the general procedure of Example II was repeated except that 1.30 g. (8.18×10^{-3} moles) of 2-chloroethyl chlorothiolformate and 1.75 g. (18.0×10^{-3} moles) of N-propargyl-n-propylamine were employed, there was obtained 1.74 g. (96.7% yield) of 2-chloroethyl N-propargyl-N-n-propylthiolcarbamate, n_D^{30} 1.5123.

Analysis.—Calculated for $C_9H_{14}ClNO$: N=6.38%. Found: N=6.19%.

Example XVII (R-2525).—When the general procedure of Example II was repeated except that 1.30 g. (8.18×10^{-3} moles) of 2-chloroethyl chlorothiolformate and 2.40 g. (18×10^{-3} moles) of 3-chloroallyl-n-propylamine were employed, there was obtained 2.03 g. (96.6% yield) 2-chloroethyl N-3-chloroallyl-n-propylthiolcarbamate, n_D^{30} 1.5196.

Analysis.—Calculated for $C_9H_{15}Cl_2NO$: N=5.47%. Found: N=5.38%.

Example XVIII (R-2526).—1.30 g. (8.18×10^{-3} moles) of 2-chloroethyl chlorothiolformate was dissolved in 25 cc. of ethyl ether and 1.75 g. (9.81×10^{-3} moles) of bis (2-chloroethylamine hydrochloride) was added. The mixture was cooled to 3° C. in an ice bath and then 10 cc. of aqueous sodium hydroxide solution containing 0.67 g. (16.8×10^{-3} moles) of sodium hydroxide was slowly added. After the addition was complete, the reaction mixture was allowed to warm up to room temperature and was then worked up in the same manner as Example II. There was obtained 1.96 g. (90.3% yield) of 2-chloroethyl N,N-bis(2-chloroethyl)thiolcarbamate, n_D^{30} 1.5381.

Analysis.—Calculated for $C_7H_{12}Cl_3NO$: N=5.29%. Found: N=5.49%.

Example XIX (R-2527).—When the general procedure of Example XVIII was repeated except that 1.30 g. (8.18×10^{-3} moles) of 2-chloroethyl chlorothiolformate, 2.03 g. (9.81×10^{-3} moles) of bis (2-chloropropylamine) hydrochloride and 0.67 g. (16.8×10^{-3} moles) of sodium hydroxide were employed, there was obtained 2.19 g. (91.3% yield) of 2-chloroethyl N,N-bis (2-chloropropyl) thiolcarbamate, n_D^{30} 1.5196.

Analysis.—Calculated for $C_9H_{16}Cl_3NO$: N=4.78%. Found: N=4.92%.

Example XX (R-2626).—3.8 g. (0.052 mole) of diethylamine dissolved in 50 cc. of ethyl ether was added to 2.0 g. (0.05 mole) of sodium hydroxide dissolved in 50 cc. of water. The mixture was cooled to 5° C. and then 8.7 g. (0.05 mole) of 3-chloropropyl chlorothiolformate was added dropwise with stirring maintaining the temperature between 5–10° C. The mixture was then allowed to warm up to room temperature and was then worked up in the same manner as Example II. There was obtained 7.5 g. (71.3% yield) of 3-chloropropyl N,N-di-ethylthiolcarbamate, B.P. (10 mm.) 142.0–142.8° C., n_D^{30} 1.4989.

Analysis.—Calculated for $C_8H_{16}ClNO$: Cl=16.90%; N=6.68%. Found: Cl=17.01%; N=6.66%.

Example XXI (R-2629).—When the general procedure of Example XX was repeated except that 5.3 g. (0.052 mole) of di-n-propylamine, 8.7 g. (0.05 mole) of 3-chloropropyl chlorothiolformate and 2.0 g. (0.05 mole) of sodium hydroxide were employed, there was obtained 6.4 g. (54.0% yield) of 3-chloropropyl N,N-di-n-propylthiolcarbamate, B.P. (10 mm.) 158.5–159.0° C., n_D^{30} 1.4925.

Analysis.—Calculated for $C_{10}H_{20}ClNO$: Cl=14.91%; N=5.89%. Found: Cl=15.12%; N=5.78%.

Example XXII (R-2632).—When the general procedure of Example XX was repeated except that 5.3 g. (0.052 mole) of N-ethyl-n-butylamine, 8.7 g. (0.05 mole) of 3-chloropropyl chlorothiolformate and 2.0 g. (0.05 mole) of sodium hydroxide were employed, there was obtained 7.5 g. (63% yield) of 3-chloropropyl N-ethyl-N-n-butylthiolcarbamate, B.P. (10 mm.) 161.5–162.0° C., n_D^{30} 1.4929.

Analysis.—Calculated for $C_{10}H_{20}ClNOS$: Cl=14.91%; N=5.89%. Found: Cl=14.91%; N=5.81%.

Example XXIII (R-2630).—When the general procedure of Example XX was repeated except that 5.1 g. (0.052 mole) of diallylamine, 8.7 g. (0.05 mole) of 3-chloropropyl chlorothiolformate and 2.0 g. (0.05 mole) of sodium hydroxide were employed, there was obtained 8.9 g. (76.5% yield) of 3-chloropropyl N,N-diallylthiocarbamate, B.P. (10 mm.) 159.0–159.5° C., n_D^{30} 1.5147.

Analysis.—Calculated for $C_{10}H_{16}ClNOS$: Cl=15.17%; N=5.99%. Found: Cl=15.08%; N=5.85%.

Example XXIV (R-2634).—When the general procedure of Example XX was repeated except that 11.8 g. (0.103 moles) of N-methallyl-n-propylamine, 17.3 g. (0.10 mole) of 3-chloropropyl chlorothiolformate and 4.0 g. (0.10 mole) of sodium hydroxide were employed, there was obtained 19.7 g. (78.8% yield) of 3-chloropropyl N-methallyl-N-n-propylthiocarbamate, B.P. (10 mm.) 164.0–164.1° C., n_D^{30} 1.5013.

Analysis.—Calculated for $C_{11}H_{20}ClNOS$: Cl=14.19%; N=5.61%. Found: Cl=13.94%; N=5.53%.

Example XXV (R-2636).—When the general procedure of Example XX was repeated except 5.8 g. (0.052 mole) of N-methallylallylamine, 8.7 g. (0.05 mole) of 3-chloropropyl chlorothiolformate and 2.0 g. of sodium hydroxide were employed, there was obtained 8.9 g. (71.6% yield) of 3-chloropropyl N-methallyl-N-allylthiocarbamate, B.P. (10 mm.) 163.5–164.0° C., n_D^{30} 1.5113.

Analysis.—Calculated for $C_{11}H_{18}ClNOS$: Cl=14.31%; N=5.65%. Found: Cl=14.51%; N=5.69%.

Example XXVI (R-2640).—When the general procedure of Example XX was repeated except 4.0 g. (0.03 mole) of N-2-chloroallyl-n-propylamine, 5.0 g. (0.029 mole) of 3-chloropropyl chlorothiolformate and 2.0 g. (0.05 mole) of sodium hydroxide were employed, there was obtained 6.9 g. (87.5% yield) of 3-chloropropyl N-2-chloroallyl-N-n-propylthiocarbamate, n_D^{30} 1.5148.

Analysis.—Calculated for $C_{10}H_{17}Cl_2NOS$: Cl=26.24%. Found: Cl=26.47%. Molar refraction: Calcd.: 69.52. Found: 69.56.

Example XXVII (R-2641).—When the general procedure of Example XX was repeated except that 3.9 g. (0.03 mole) of N-3-chloroallylallylamine, 5.0 g. (0.029 mole) of 3-chloropropyl chlorothiolformate and 2.0 g. (0.05 mole) of sodium hydroxide were employed, there was obtained 6.8 g. (87.2% yield) of 3-chloropropyl N-3-chloroallyl-N-allylthiocarbamate, n_D^{30} 1.5312.

Analysis.—Calculated for $C_{10}H_{15}Cl_2NOS$: Cl=26.44%. Found: Cl=26.64%. Molar refraction: Calcd.: 69.20. Found: 68.70.

Example XXVIII (R-2643).—When the general procedure of Example XX was repeated except that 5.1 g. (0.052 mole) of N-propargyl-n-propylamine, 8.7 g. (0.05 mole) of 3-chloropropyl chlorothiolformate, and 2.0 g. (0.05 mole) of sodium hydroxide were employed, there was obtained 6.2 g. (53.1% yield) of 3-chloropropyl N-propargyl-N-n-propylthiocarbamate, B.P. (10 mm.) 167.0–167.5° C., n_D^{30} 1.5117.

Analysis.—Calculated for $C_{10}H_{16}ClNOS$: Cl=15.17%; N=5.99%. Found: Cl=15.31%; N=5.83%.

Example XXIX (R-2644).—When the general procedure of Example XVIII was repeated except that 5.4 g. (0.03 mole) of bis(2-chloroethylamine) hydrochloride, 5.0 g. (0.029 mole) of 3-chloropropyl chlorothiolformate and 2.4 g. (0.06 mole) of sodium hydroxide were employed, there was obtained 7.7 g. (95% yield) of 3-chloropropyl N,N-bis(2-chloroethyl) thiolcarbamate, n_D^{30} 1.5330.

Analysis.—Calculated for $C_8H_{14}Cl_3NOS$: Cl=38.17%. Found: Cl=38.39%.

Example XXX (R-2633).—When the general procedure of Example XX was repeated except that 5.2 g. (0.052 mole) of N-allyl-n-propylamine, 8.7 g. (0.05 mole) of 3-chloropropyl chlorothiolformate and 2.0 g.

(0.05 mole) of sodium hydroxide were employed, there was obtained 8.47 g. (71.8% yield) of 3-chloropropyl N-allyl-n-propylthiocarbamate, B.P. (10 mm.) 159.5–160.0° C., n_D^{30} 1.5037.

Analysis.—Calculated for $C_{10}H_{18}ClNOS$: Cl=15.04%; N=5.94%. Found: Cl=15.13%; N=5.96%.

Example XXXI (R-2939).—A 500 cc. 4 neck flask was provided with stirrer, thermometer, condenser and gas inlet tube. A solution of 7.3 g. (0.10 mole) of diethylamine and 10.1 g. (0.10 mole) of triethylamine in 150 cc. of tert. butyl alcohol was charged to the flask and then 10 g. (0.17 mole) of carbonyl sulfide was bubbled into the amine solution with rapid stirring maintaining the temperature between 15–20° C. with ice cooling. To this 15 solution at 15° C. was then added rapidly 56.4 g. (0.30 mole) of 1,2-dibromoethane. The mixture was then heated slowly to 45° C. and was maintained at 45–50° C. for 1½ hours. The thin slurry was then heated to reflux, 125 cc. of solvent was distilled, the residual slurry was cooled to room temperature, diluted with 200 cc. of petroleum ether, B.P. 30–60° C., and successively washed with 2–50 cc. portions of 5% hydrochloric acid and 2–50 cc. portions of water. The organic phase was then dried over anhydrous magnesium sulfate, filtered, 25 and the filtrate was concentrated on the steam bath. The residual liquid was then fractionally distilled through an 18" Podbielniak Heli-Grid Fractional Distillation Column. There was obtained 12.6 g. (52.5% yield) of 2-bromoethyl N,N-diethylthiocarbamate, B.P. (10 mm.) 139–140° C., n_D^{30} 1.5229.

Analysis.—Calculated for $C_7H_{14}BrNOS$: N, 5.83%. Found: N, 5.97%.

Example XXXII (R-2941).—When the general procedure of Example XXXI was repeated except that 10.1 g. (0.10 mole) of di-n-propylamine, 10.1 g. (0.10 mole) of triethylamine, 10 g. (0.17 mole) of carbonyl sulfide, 56.4 g. (0.30 mole) of 1,2-dibromoethane and 150 cc. of tert. butyl alcohol were employed, there was obtained 13.5 g. (50.2% yield) of 2-bromoethyl N,N-di-n-propylthiocarbamate, B.P. (10 mm.) 155.5–156.0° C., n_D^{30} 1.5122.

Analysis.—Calculated for $C_9H_{18}BrNOS$: N, 5.22%. Found: N, 4.95%.

Example XXXIII (R-2946).—When the general procedure of Example XXXI was repeated except that 10.1 g. (0.10 mole) of N-ethyl-n-butylamine, 10.1 g. (0.10 mole) of triethylamine, 10 g. (0.17 mole) of carbonyl sulfide, 56.4 g. (0.30 mole) of 1,2-dibromoethane and 150 cc. of tert. butyl alcohol were employed, there was obtained 9.6 g. (35.8% yield) of 2-bromoethyl N-ethyl-N-n-butylthiocarbamate, B.P. (10 mm.) 157.0–159.5° C., n_D^{30} 1.5118.

Analysis.—Calculated for $C_9H_{18}BrNOS$: N, 5.22%. Found: N, 5.44%.

Example XXXIV (R-2948).—When the general procedure of Example XXXI was repeated except that 9.7 g. (0.10 mole) of diallylamine, 10.1 g. (0.10 mole) of triethylamine, 10 g. (0.17 mole) of carbonyl sulfide, 56.4 g. (0.30 mole) of 1,2-dibromoethane and 150 cc. of tert. butyl alcohol were employed, there was obtained 9.8 g. (37.0% yield) of 2-bromoethyl N,N-diallylthiocarbamate, B.P. (10 mm.) 154.0–156.5° C., n_D^{30} 1.5368.

Analysis.—Calculated for $C_9H_{18}BrNOS$: N, 5.30%. Found: N, 5.51%.

Example XXXV (R-2949).—When the general procedure of Example XXXI was repeated except that 9.9 g. (0.10 mole) of N-allyl-n-propylamine, 10.1 g. (0.10 mole) of triethylamine, 10 g. (0.17 mole) of carbonyl sulfide, 56.4 g. (0.30 mole) of 1,2-dibromoethane and 150 cc. of tert. butyl alcohol were employed, there was obtained 14.7 g. (55.3% yield) of 2-bromoethyl N-allyl-N-n-propylthiocarbamate, B.P. (10 mm.) 155.0–156.5° C., n_D^{30} 1.5270.

Analysis.—Calculated for $C_9H_{18}BrNOS$: N, 5.26%. Found: N, 5.22%.

Example XXXVI (R-2952).—When the general procedure of Example XXXI was repeated except that 9.9 g. (0.10 mole) of N-methyllethylamine, 10.1 g. (0.10 mole) of triethylamine, 10 g. (0.17 mole) of carbonyl sulfide, 56.4 g. (0.30 mole) of 1,2-dibromoethane and 150 cc. of tert. butyl alcohol were employed, there was obtained 12.8 g. (48.0% yield) of 2-bromoethyl N-methyl-N-ethylthiolkarbamate, B.P. (10 mm.) 151.0–153.0° C., n_D^{20} 1.5267.

Analysis.—Calculated for $C_9H_{16}BrNOS$: N, 5.26%. Found: N, 5.45%.

Example XXXVII (R-2958).—When the general procedure of Example XXXI was repeated except that 11.1 g. (0.10 mole) of N-methylallylamine, 10.1 g. (0.10 mole) of triethylamine, 10 g. (0.17 mole) of carbonyl sulfide, 56.4 g. (0.30 mole) of 1,2-dibromoethane and 150 cc. of tert. butyl alcohol were employed, there was obtained 12.6 g. (45.3% yield) of 2-bromoethyl N-methyl-N-allylthiolkarbamate, B.P. (10 mm.) 160.0–161.0° C., n_D^{20} 1.5320.

Analysis.—Calculated for $C_{10}H_{16}BrNOS$: N, 5.03%. Found: N, 5.25%.

Example XXXVIII (R-2962).—When the general procedure of Example XXXI was repeated except that 7.3 g. (0.10 mole) of diethylamine, 10.1 g. (0.10 mole) of triethylamine, 10 g. (0.17 mole) of carbonyl sulfide, 60.6 g. (0.30 mole) of 1,3-dibromopropane and 150 cc. of tert. butyl alcohol were employed, there was obtained 15.3 g. (60.2% yield) of 3-bromopropyl N,N-diethylthiolkarbamate, B.P. (10 mm.) 152.5–153.5° C., n_D^{20} 1.5166.

Analysis.—Calculated for $C_8H_{16}BrNOS$: N, 5.51%. Found: N, 5.57%.

Example XXXIX (R-2969).—When the general procedure of Example XXXI was repeated except that 10.1 g. (0.10 mole) of di-n-propylamine, 10.1 g. (0.10 mole) of triethylamine, 10 g. (0.17 mole) of carbonyl sulfide, 60.6 g. (0.30 mole) of 1,3-dibromopropane and 150 cc. of tert. butyl alcohol were employed, there was obtained 18.4 g. (65.4% yield) of 3-bromopropyl N,N-di-n-propylthiolkarbamate, B.P. (10 mm.) 169.5–171.0° C., n_D^{20} 1.5078.

Analysis.—Calculated for $C_{10}H_{20}BrNOS$: N, 4.96%. Found: N, 5.05%.

Example XL (R-2978).—When the general procedure of Example XXXI was repeated except that 8.7 g. (0.10 mole) of N-methyl-n-butylamine, 10.1 g. (0.10 mole) of triethylamine, 10 g. (0.17 mole) of carbonyl sulfide, 60.6 g. (0.30 mole) of 1,3-dibromopropane and 150 cc. of tert. butyl alcohol were employed, there was obtained 14.7 g. (54.8% yield) of 3-bromopropyl N-n-butyl-N-methylthiolkarbamate, B.P. (10 mm.) 164.5–167.0° C., n_D^{20} 1.5111.

Analysis.—Calculated for $C_9H_{18}BrNOS$: N, 5.22%. Found: N, 5.13%.

Example XLI (R-2984).—When the general procedure of Example XXXI was repeated except that 9.7 g. (0.10 mole) of diallylamine, 10.1 g. (0.10 mole) of triethylamine, 10 g. (0.17 mole) of carbonyl sulfide, 60.6 g. (0.17 mole) of 1,3-dibromopropane and 150 cc. of tert. butyl alcohol were employed, there was obtained 12.2 g. (43.4% yield) of 3-bromopropyl N,N-diallylthiolkarbamate, B.P. (10 mm.) 165.0–167.0° C., n_D^{20} 1.5283.

Analysis.—Calculated for $C_{10}H_{16}BrNOS$: N, 5.03%. Found: N, 5.00%.

Example XLII (R-2987).—When the general procedure of Example XXXI was repeated except that 9.9 g. (0.10 mole) of N-allyl-n-propylamine, 10.1 g. (0.10 mole) of triethylamine, 10 g. (0.17 mole) of carbonyl sulfide, 60.6 g. (0.30 mole) of 1,3-dibromopropane and 150 cc. of tert. butyl alcohol were employed, there was obtained 17.8 g. (63.6% yield) of 3-bromopropyl N-allyl-N-n-propylthiolkarbamate, B.P. (10 mm.) 169.0–170.0° C., n_D^{20} 1.5190.

Analysis.—Calculated for $C_{10}H_{18}BrNOS$: N, 5.00%. Found: N, 4.95%.

Example XLIII (R-2990).—When the general procedure of Example XXXI was repeated except that 9.9 g. (0.10 mole) of N-methyllethylamine, 10.1 g. (0.10 mole) of triethylamine, 10 g. (0.17 mole) of carbonyl sulfide, 60.6 g. (0.30 mole) of 1,3-dibromopropane and 150 cc. of tert. butyl alcohol were employed, there was obtained 15.4 g. (55.0% yield) of 3-bromopropyl N-methyl-N-ethylthiolkarbamate, B.P. (10 mm.) 164.0–165.5° C., n_D^{20} 1.5200.

Analysis.—Calculated for $C_{10}H_{18}BrNOS$: N, 5.00%. Found: N, 4.99%.

The compounds of the present invention have been tested as herbicides and found very effective as the following typical tests show. Some of the compounds are quite selective in their action and can be used to eradicate or control one type of plant, while another type of plant is relatively unaffected.

In making the following tests, seeds were planted in 3" pots and shortly thereafter the compound under test was applied to the pots in a drench at the rate of 365 pounds per acre. The pots were placed in a greenhouse and watered at suitable intervals and the germination and growth of the seeds was compared with similarly planted seeds to which no herbicide was added. In each case, germination was reported on the scale of 0–100%, while growth was reported on a scale of 0–10, based on the seeds which germinated. Thus, 100–10 indicates normal germination and normal growth.

The following data were obtained.

Compound	Oats		Cucumbers		Radish	
	Germ.	Growth	Germ.	Growth	Germ.	
					Growth	Growth
R-2215	0		0		75	4

¹ Percent germination. ² Growth.

2 Growth.

The compounds of the present invention may be used in pre-emergence or post-emergence herbicides and may be applied in a variety of ways at various concentrations. They may be combined with suitable carriers and applied as dusts, sprays or drenches. The amount applied will depend on the nature of the seeds or plants to be controlled and the rate of application may vary from 1 to 500 pounds per acre. One particularly advantageous way of applying the compounds is as a narrow band along a row crop, straddling the row.

We claim:

1. The method of combating weeds comprising applying a phytotoxic amount to the soil of a compound:

wherein R_1 is selected from lower chloroalkyl and bromo-alkyl radicals, R_2 is a member selected from the group consisting of a lower alkyl radical, a lower chloroalkyl

11

radical, a lower alkenyl radical, a lower chloroalkenyl radical and an alkynyl radical, and R₃ is a member of the group consisting of a lower alkyl radical, a lower cycloalkyl radical, a lower chloroalkyl radical and a lower alkenyl radical.

2. The method of claim 1 wherein the compound is applied at the rate of 1 to 500 pounds per acre.

3. The method of claim 1 wherein the compound is 2-chloroethyl N,N-di-n-propylthiolcarbamate.

4. The method of claim 1 wherein the compound is 10 2-bromoethyl N,N-di-n-propylthiolcarbamate.

5. The method of claim 1 wherein the compound is 2-chloroethyl N-ethyl-N-cyclohexylthiolcarbamate.

6. The method of claim 1 wherein the compound is 15 N-allyl-N-isopropylthiolcarbamate.

7. The method of claim 1 wherein the compound is 20 2-bromoethyl N-methallyl-N-ethylthiolcarbamate.

8. A herbicidal composition comprising a major proportion of a herbicidal adjuvant as carrier and a minor but phytotoxic concentration of a phytotoxic compound of the structure

where R and R' represent lower alkyl and A represents halogen substituted lower alkyl.

9. The method of destroying vegetation which comprises applying to germinating seedlings a phytotoxic amount of a phytotoxic composition containing as the essential active ingredient a compound of the structure

where R and R' represent lower alkyl and A represents halogen-substituted lower alkyl.
